(57) **CLAIM**

The ornamental design for a bone staple, substantially as shown and described.

DESCRIPTION

FIG. 1 is a first perspective view of a bone staple according to an embodiment of the design.

FIG. 2 is a second perspective view of the bone staple shown in FIG. 1.

FIG. 3 is a first end view of the bone staple shown in FIG. 1.

FIG. 4 is a second end view of the bone staple shown in FIG. 1.

FIG. 5 is a first side view of the bone staple shown in FIG. 1.

FIG. 6 is a second side view of the bone staple shown in FIG. 1.

FIG. 7 is a front view of the bone staple shown in FIG. 1.

FIG. 8 is a back view of the bone staple shown in FIG. 1.

FIG. 9 is a first perspective view of a bone staple according to another embodiment of the design.

FIG. 10 is a second perspective view of the bone staple shown in FIG. 9.

FIG. 11 is a first end view of the bone staple shown in FIG. 9.

FIG. 12 is a second end view of the bone staple shown in FIG. 9.

FIG. 13 is a first side view of the bone staple shown in FIG. 9.

FIG. 14 is a second side view of the bone staple shown in FIG. 9.

FIG. 15 is a front view of the bone staple shown in FIG. 9; and,

FIG. 16 is a back view of the bone staple shown in FIG. 9. Portions shown in broken lines are for illustrative purposes only and form no part of the claimed design.

1 Claim, 8 Drawing Sheets
